UNITED STATES PATENT OFFICE.

GEORGE MEADE, OF ALLIANCE, NEBRASKA.

RAIL-BRACE.

1,257,511.

Specification of Letters Patent. Patented Feb. 26, 1918.

Application filed November 17, 1917. Serial No. 202,535.

To all whom it may concern:

Be it known that I, GEORGE MEADE, a citizen of the United States, residing at Alliance, in the county of Box Butte and State of Nebraska, have invented certain new and useful Improvements in Rail-Braces, of which the following is a specification, reference being had to the accompanying drawings.

10 This invention relates to certain improvements in rail braces and it is an object of the invention to provide a novel and improved device of this general character which serves effectually to hold a rail from spreading or turning over and which also coacts with a rail in such a manner as to prevent the separation of adjacent ends of a break in a rail.

It is also an object of the invention to 20 provide a novel and improved device of this general character which, in addition to bracing a rail, serves to reduce materially the slipping or creeping of the ties embodied in a track structure.

25 The invention consists in the details of construction and in the combination and arrangement of the several parts of my improved rail brace whereby certain important advantages are attained and the device is 30 rendered simpler, less expensive and otherwise more convenient and advantageous for use, all as will be hereinafter more fully set forth.

The novel features of the invention will 35 be hereinafter definitely claimed.

In order that my invention may be the better understood, I will now proceed to describe the same with reference to the accompanying drawings, wherein—

40 Figure 1 is a view in top plan illustrating braces constructed in accordance with my invention in applied position, a portion of the rail being in section and the holding spikes coacting with one of the braces being 45 omitted; and

Fig. 2 is a sectional view taken substantially on the line 2—2 of Fig. 1.

As disclosed in the accompanying drawings R denotes a rail mounted upon the ties 50 T and engaged with each of the ties T is a bracing member M coacting with the outer side of the rail R.

Each of the members M comprises a plate 1 adapted to fit snugly between the ball 2

and flange 3 of the rail. Extending outwardly from the plate 1 at substantially its longitudinal center is the arm 4 which is also connected to said plate 1 substantially midway the longitudinal margins thereof. The outer end portion of the arm 4 is downwardly directed, at 5, and integrally connected with the plate 6 adapted to rest upon the top surface of a tie T. The plate 6 is provided in its marginal portions with the notches or recesses 7 to receive the holding 65 spikes 8.

The plate 1 is of a length materially in excess of the adjacent tie T so that, when the member M is in applied position, the plate 1 will extend beyond opposite sides 70 of the tie and in close proximity to the plates 1 carried by the adjacent ties. By this arrangement it will be understood that should a tie T creep or slip its movement will be limited by contact of an end portion of the 75 plate 1 carried by such tie with the adjacent plate.

It will also be understood that by having the plate elongated the formation of a "leap" or the separation of the ends of a brace in 80 a rail will be prevented as the plate 1 serves to hold the rail from falling over or from moving upward. My improved brace also prevents a broken rail from falling between the ties so that the possibility of an accident 85 from such a cause is eliminated.

In practice it is particularly desired that my improved braces be employed in connection with curves in the trackway although I do not wish to be understood as limiting myself in this respect. It is also preferred that the plates 1 be of such a length as to have adjacent plates, when the braces are applied, separated a distance sufficient only to compensate for expansion and contraction. 90

From the foregoing description, it is thought to be obvious that a rail brace constructed in accordance with my invention is particularly well adapted for use by reason of the convenience and facility with which it may be assembled and it will also be obvious that my invention is susceptible of some change and modification without materially departing from the principle and spirit thereof and for this reason I do not wish to be understood as limiting myself to the precise arrangement and formation of the several parts herein shown in carrying out my 100 105

invention in practice except as hereinafter claimed.

I claim:

In combination with a rail and supporting ties therefor, brace members coacting with the rail and carried by the ties, each of said brace members including a plate fitting between the ball and flange of the rail

and of a length to extend beyond opposite sides of the tie but terminating inwardly of adjacent ties, the extremities of the plate terminating in close proximity to the plates of adjacent brace members. 10

In testimony whereof I hereunto affix my signature.

GEORGE MEADE.
